(57) **CLAIM**

The ornamental design for a switch for a laser aiming light, as shown and described.

DESCRIPTION

FIG. 1 is a perspective view of a switch for a laser aiming light showing my new design, the dashed lines are shown to illustrate environment only and form no part of the claimed design;

FIG. 2 is a top view thereof;

FIG. 3 is a left side view thereof;

FIG. 4 is a bottom view thereof;

FIG. 5 is a rear view thereof taken from the right side of the view shown in FIG. 4;

FIG. 6 is a front view thereof; and,

FIG. 7 is a right side view thereof.
